UNITED STATES PATENT OFFICE.

JOHN W. KAUFMANN, OF BALTIMORE, MARYLAND.

REPRODUCER FOR TALKING-MACHINES.

1,354,197.

Specification of Letters Patent. Patented Sept. 28, 1920.

Application filed July 17, 1919. Serial No. 311,623.

To all whom it may concern:

Be it known that I, JOHN W. KAUFMANN, a citizen of the United States, and a resident of Baltimore, in the State of Maryland, have invented certain new and useful Improvements in Reproducers for Talking-Machines, of which the following is a specification.

My invention is an improvement in reproducers, and has for its object to provide a new and improved connection between the needle and the diaphragm controlling lever, which will eliminate the usual rigidity between these parts and which will intensify the movement of the needle during its transmission to the diaphragm.

In the drawings:

Figure 1 is a perspective view of the improved reproducer;

Fig. 2 is a similar view of the holding bracket for the transmission member;

Fig. 3 is a similar view of the diaphragm controlling lever;

Fig. 4 is a perspective view of one of the connecting brackets;

Fig. 5 is a longitudinal section;

Figs. 6 and 7 are views similar to Fig. 5, showing modified constructions;

Fig. 8 is a side view showing a modified form of needle holder.

In the embodiment of the invention shown in Figs. 1 to 5, the case 1 of the reproducer is connected to the tone arm 2 and a bracket plate 3 is secured between the case and the tone arm, this bracket plate having a width approximately that of a diameter of the casting and being of considerably greater length, as shown, so that at the end remote from the needle it will extend well beyond the case, and the ends of the bracket plate are bent laterally, as shown at 4 and 5.

A resilient member 6 is provided for connecting the needle 7 with the diaphragm controlling lever 8, this plate being connected indirectly at one end with the needle and indirectly at the other with the lever. At the lever end a connecting frame of substantially rectangular form and consisting of sides 9 and integral ends 10 is provided for connecting the plate 6 with the lever 8. The sides 9 of this frame have perforated enlargements 11 intermediate their ends for receiving the shaft 12 which pivotally connects the frame and the adjacent angle portion 4 of the bracket plate. This shaft 12

is extended at its ends beyond the enlargements 11, and the said ends are journaled in openings in angle brackets 13 which are secured to the outer face of the portion 4. Referring to Fig. 1 it will be seen that these laterally bent portions 4 and 5 of the bracket plate are notched or recessed intermediate their ends, the notch or recess of the portion 4 being for receiving the frame 9—10, while that in the portion 5 is for a purpose to be presently described.

The resilient plate 6 is of tapering form, being of greatest width at the frame 9—10, and decreasing in width toward the needle, and at the end adjacent to the frame the plate passes over the ends 10 and beneath the shaft 12, and is firmly held to the frame by the shaft, the large end of the plate being bent to form a lip 14 which engages behind the adjacent end 10. At the shaft 12 the plate has a longitudinally extending slot 15 for receiving a perforated lug 17 on the lever 8. This lug receives the shaft 12 and the said lug firmly connects the lever to the shaft, so that the lever will move with the frame, it being understood that the lever engages the ends 10 of the frame on the under side of the frame. The perforation of the lug 17 is so arranged that the shaft will tightly hold the upper edge of the lever against the lower edges of the ends.

The needle holder 18 is secured to the small end of the spring 6 by means of screws 19 or the like, and it has the usual opening for receiving the needle 7 which is secured in place by the usual set screw 23. This needle holder 18 has journal pins 20 which engage openings in other angle brackets 21 corresponding to the brackets 13 at the opposite end of the bracket plate 3. These bracket plates are held to the laterally extending portions 4—5 of the bracket plate by screw bolts, screws or the like. Referring to Fig. 3, it will be seen that the lever 8 has an angular lug 22 at the end remote from the frame 9—10 for connection with the diaphragm.

In operation, when the needle 7 is in engagement with the groove of a record as shown in Fig. 1, it will be vibrated by the undulations in the groove, and will move with it the needle holder 18 which is rigidly secured to the plate 6. The vibrations of the needle will be transmitted by the plate 6 to the frame 9—10 and to the diaphragm 110.

lever 8, which will vibrate the diaphragm in synchronism with the needle, but with amplified movement, due to the leverage between the parts and to the increasing strength of the plate 6, due to increasing width.

In the embodiment of the invention shown in Fig. 6 the frame 24 which corresponds to the frame 9—10 of Fig. 1 is supported at 10 one end of the bracket plate 25 in the same manner as the frame 9—10, but the shaft 26 which pivotally connects the frame to the bracket plate is in line with the diaphragm of the sound box 27. Because of 15 this arrangement it is necessary that the frame 24 set at an angle to the plane of the diaphragm, and the reproducing lever 28 is bent to conform with the changed position of the parts.

20 The resilient plate 29 which corresponds to the plate 6 of Fig. 1 is engaged by the frame 24 in the same manner, but this plate consists of two portions extending at an obtuse angle with respect to each other, one 25 engaging the frame 24 and the other extending between the said frame and the needle holder 30 which is pivoted to the opposite end of the bracket plate 25. The operation is precisely the same as the form shown in 30 Fig. 1, the only difference being in the arrangement of the pivotal mounting of the frame 24.

In Fig. 7 the resilient plate 31 which corresponds to the plate 6 is sinuous, as shown, 35 being curved in opposite directions between the frame 32 and the needle holder 33. The frame 32 is pivoted to the bracket plate 33 which corresponds to the plate 3 of Fig. 1 at one end thereof, and the needle holder is 40 pivoted to the other end. The reproducing lever 34 is connected to the frame in the same manner as the lever 8 of Fig. 1. This arrangement is somewhat more responsive than that shown in Fig. 1. It will be obvious that due to the sinuous contour of the 45 connecting plate 31 a large amount of relative movement is permitted between the frame 32 and the needle holder 33, while at the same time they are normally held in a 50 certain predetermined relation with respect to each other. It will be obvious that the needle holder may be connected to the resilient plate 6, 29 or 31, as the case may be, in the same manner as the frame 9—10 is 55 connected to the said plate, that is, the form of needle holder shown may be replaced by that shown in Fig. 8. In this arrangement the needle holder 35 is integral with the cross bar 36 of a substantially rectangular frame 37 similar to the frame 9—10 of Fig. 60 1. That end of the plate 38 which corre-

sponds to the plate 6 adjacent to the frame 37 is passed beneath the end members of the frame and above the cross bar 36 which, as shown, is beveled or substantially triangular, the plate 38 engaging the apex of the cross bar.

It will be noticed, referring to Fig. 5, that the bracket plate 3 is held to the reproducer by means of a ring 40, which is secured to 7 the bracket plate in any suitable or desired manner, as, for instance, by brazing, and this ring has an annular rib at its inner edge which fits about the reproducer and may be secured thereto by means of set 7 screws 41 or the like.

I claim:

1. In reproducers, a bracket plate supported by the sound box and extending beyond the same at one end of the plate, said plate having at each end a laterally bent portion, a substantially rectangular frame pivoted to one of the laterally bent portions to swing on a central axis transverse to the frame, a needle holder pivoted to the other to swing on an axis parallel with that upon which the frame swings, and a resilient transmitting plate connecting the frame to the needle holder and extending transversely of the diaphragm.

2. In reproducers, the combination with the sound box, of a bracket plate supported by the sound box and having at each end an angular portion extending toward the diaphragm of the sound box, a needle holder pivoted to one end of the plate, a support for the reproducer lever pivoted to the other end of the plate to swing on an axis parallel with that upon which the needle holder swings, and a resilient connection between 9 the needle holder and the said support for constraining them to move together.

3. In a reproducer, the combination with the sound box, of a radial extension at one side thereof, a reproducing lever connected 10 with the diaphragm at its inner end and pivotally mounted on the extension at its outer end, a needle support pivoted to the sound box opposite the pivotal connection of the lever, and a resilient connection between the 11 pivotal connection of the reproducer lever and the needle support.

4. In a reproducer, the combination with the sound box, the needle support and the reproducing lever, of an extension extending 11 radially from the sound box, a pivotal support for the outer end of the reproducing lever at the outer end of the extension, and a resilient connection between the needle support and the pivotal mounting of the 12 reproducing lever.

JOHN W. KAUFMANN.
